UNITED STATES PATENT OFFICE.

SCOTT H. HULL, OF OSKALOOSA, IOWA.

DESIGN FOR A HARNESS-LOOP.

SPECIFICATION forming part of Design No. 27,753, dated October 19, 1897.

Application filed August 23, 1897. Serial No. 649,279. Term of patent 14 years.

To all whom it may concern:

Be it known that I, SCOTT H. HULL, a citizen of the United States, residing at Oskaloosa, in the county of Mahaska and State of Iowa, have invented and produced a new and original Design for Checkrein Guide-Loops; and I do hereby declare the following to be a full, clear, and exact description of the same, reference being had to the accompanying drawings, forming a part thereof.

The invention has relation to a new and useful design for a checkrein guide-loop for harness. It relates to the entire configuration of the same.

My invention relates particularly to the loop as illustrated in the accompanying drawings, in which—

Figure 1 is a perspective view of a checkrein-loop embodying my design. Fig. 2 is a bottom plan view of the same.

The leading features of my design appear in the following description:

1 represents the base or body of the loop, and 2 2 the upwardly and inwardly curved arms.

3 represents a hemispherical boss centrally disposed between the arms 2 2 and on top of the base or body of the loop. 25

4 represents a split shank or rivet the arms of which have their lower ends beveled in the inner faces thereof at 5. 30

6 represents an annular shoulder on the under side of the base or body of the loop and encircling the upper end of the said shank or rivet.

Having thus fully described my invention, 35 what I claim as new and useful, and desire to secure by Letters Patent of the United States, is—

The design for a harness-loop, substantially as herein shown and described. 40

In testimony whereof I affix my signature in presence of two witnesses.

SCOTT H. HULL.

Witnesses:

JOHN R. BARNES,
MARTIN WALRAVEN.
